UNITED STATES PATENT OFFICE.

DANL. WALROTH, OF CHITTENANGO, AND LUCIUS EVANS, OF MANLIUS, NEW YORK.

MACHINE FOR SEPARATING IRON FROM FURNACE-CINDERS.

Specification of Letters Patent No. 9,493, dated December 21, 1852.

To all whom it may concern:

Be it known that we, DANIEL WALROTH, of Chittenango, in the county of Madison, and LUCIUS EVANS, of Manlius, in the county of Onondaga, State of New York, have invented a new Machine for Separating Iron from Furnace-Cinders; and we do hereby declare that the following is a full and exact description of the said invention and of the construction and operation of such machine, reference being had to the annexed drawings, making a part of this specification, in which—

Figure 1, is a perspective view. Letter A, represents a hollow cylinder for tumbling the cinders and iron and retaining the coarser parts of the iron. Letter B represents a cylinder in which the fan D is made to revolve by means of the wheel H throwing a current of air under the cylinder A and separating the cinders from the iron as they drop through the apertures J J.

e, e, e, e, e, e, represent iron staves which are fastened upon the heads F, F, and constitute the cylinder A. These staves are placed far enough apart to allow the cinders when broken to fall through between the apertures J, J. G represents the wheel by which the cylinder A is made to revolve. I represents an aperture in the cylinder B, through which a current of air is made to pass by means of the fan. D represents the frame which supports the machinery.

What we claim and desire to secure by Letters Patent, is—

The combination of the revolving breaking, and sifting cylinder with the fan or its equivalent, substantially in the manner, and for the purposes specified.

DANIEL WALROTH.
LUCIUS EVANS.

Witnesses:

JACIUS FRENCH,
CATHARINE FRENCH.
